ANTOINE B. PINARD, OF SAN JOSE, CALIFORNIA.

SHIPPING CAGE FOR BEES.

Application filed February 23, 1927. Serial No. 170,321.

In shipping a queen bee and her companions from one point to another it is customary to confine them in a small ventilated cage provided with means whereby 5 the bees may effect their escape after a lapse of time with the assistance of the bees in the hive in which the cage is placed.

It is one object of the present invention to provide a cage of the character indicated that 10 may be quickly and easily assembled without the use of tacks or brads or similar fastening devices.

It is another object of the invention to provide a cage for the purpose specified that will 15 provide better ventilation than those now commonly used.

It is still another object of the invention to provide a cage of the character indicated that may be stacked with other similar cages and 20 fastened together for shipment without interfering with the ventilation thereof.

It is also an object of the invention to provide a cage of the character indicated that will be economical to manufacture, simple in 25 form and construction, and highly efficient in its practical application.

In the drawing:

Figure 1 is a plan view of a cage embodying my invention.

30 Figure 2 is a sectional view on line 2—2 of Figure 1.

Figure 3 is a sectional view on line 3—3 of Figure 1.

35 Figure 4 is an end view of a number of the cages stacked for shipment.

Referring more particularly to the drawing, I show at 1 a block of wood of suitable proportions, preferably oblong in shape and rectangular in elevation.

40 In one face of the block, hereinafter referred to as the top, is formed a channel 2 extending from end to end thereof as shown. This channel is so made as to form a concave upper surface to the said block as at 3, leaving two narrow upstanding side ribs as 4 and forming shoulders in opposed relation to each other as at 5.

At 6, 7 and 8 are shown three holes bored 50 a distance into the block on the channeled side thereof and the adjacent holes intersecting each other whereby to form passages therebetween as shown at 9. A smaller passage is bored through the side of the block as at 11 into the hole 8 to form a passageway thereto, and a similar small hole as 10 is bored

through the side of the block into the hole 6 to form a passageway thereto.

I show a piece of paraffined paper at 12 long enough to cover the hole 8, and a little wider than the distance between the opposed 60 faces of the ribs 4 so that when pressed downwardly into the shoulders 5 it will bow downwardly into contact with the surface 3 and overlie the hole 8.

A piece of wire screen mesh is shown at 65 13, and this is cut to substantially the same length as the block 1 and is likewise cut a little wider than the distance between the ribs 4 so that when it is pressed into place between the shoulders 5 it will closely engage the inner 70 surfaces of the two ribs and bow downwardly to contact with the surface 3 and overlie the three holes 6, 7 and 8.

As a closure for the passage 10 I provide a 75 perforated metal disc 14 having a diameter slightly greater than the diameter of the passage 10 so that when it is pressed into the passage it will bow slightly as shown, its normal resiliency causing its edge to engage the wall of the passage with sufficient force to prevent 80 its being easily extracted therefrom. The ragged edge of the disc enables it to grip the wall of the passage with but little if any, radial pressure.

To close the passage 11 I provide a disc of 85 paper 15, this disc also being of slightly greater diameter than the passage 11 so that when pressed into the passage it will snugly engage the wall of the passage and be held in position against accidental displacement.

90 Suppose now that a queen bee and a number of other bees are to be shipped in one of these cages. The compartment 8 is first filled with a plastic "candy" upon which the bees may feed, and the disc 15 pressed into position preferably against the said candy. The piece of paraffin paper 12 is now pressed into place, and then the screen wire mesh 13 is pressed into place. This screen is best placed by positioning one edge against one 95 shoulder 5 and then pressing the body into contact with the surface 3 and finally pressing the other edge down on to the other shoulder 5. In this manner the ends of the transverse wires of the screen are caused to bite 100 into the wood. Being bowed downwardly into contact with the surface 3 its natural resiliency tends to force its edges outwardly into closer engagement with the shoulders 5, and consequently it cannot be displaced by 110

accidental means. This screen holds the paper 12 in position, and functions as a ventilated closure for the top of the cage.

The bees are now introduced into the cage 5 through the passage 10, and then the disc 14 is pressed into the passage to form a ventilated closure therefor.

By means of this construction a cage is provided that may be cheaply constructed, 10 and easily assembled without the use of tacks, brads or similar fastenings. When the bees reach their destination they effect their liberation by eating through the disc 15.

Usually these cages are shipped in stacks, 15 a number of the cages being placed one upon another as shown in Figure 4 and then secured in any suitable manner as by tying with a cord 16. When stacked in this manner the cages are still perfectly ventilated 20 through the channels 2.

It is desirable that the cage be made of wood but it may be made of any material that will provide suitable engagement with the closures.

It is to be understood, of course, that while I have herein shown and described but one specific embodiment of the invention, changes in form, construction, and method of manufacture and assembly may be made within the scope of the appended claims.

I claim:

1. A bee cage comprising an open topped receptacle having a concave channel formed in the top thereof, and opposed upstanding shoulders formed on either side of said channel, and a perforated resilient closure for said opening adapted to engage the concave top surface and having a mutilated edge adapted to engage the said opposed shoulders.

2. A bee cage comprising a receptacle having an opening formed therein, and a perforated closure for the opening insertable therein and having edges formed thereon adapted to engage and rupture the side walls of the opening to obtain intimate engagement therewith whereby to hold the closure in a fixed position.

ANTOINE B. PINARD.
